PORTABLE PICTURE SCREEN

Edward J. Petrick, Park Ridge, Ill., assignor to Knox Manufacturing Company, a corporation of Illinois

Filed Apr. 24, 1959, Ser. No. 55,648

Term of patent 14 years

(Cl. D61—1)

Fig. 1 is a perspective view of a portable picture screen, showing my new design;

Fig. 2 is a top plan view, to an enlarge scale; and

Fig. 3 is a cross sectional view thereof taken on line 3—3 in Fig. 1, the cross sectioned casing being of uniform cross section throughout its length.

The dominant features of my new design are shown in solid lines in the drawing, the broken lines showing of a stand being omitted from Figs. 2 and 3 for convenience in illustration.

I claim:

The ornamental design for a portable picture screen, as shown and described.
